CLAIM

The ornamental design for an electronic calculator with solar cell, as shown and described.

DESCRIPTION

FIG. 1 is a top plan view of the electronic calculator with solar cell showing our new design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof; and

FIG. 7 is a right front perspective view thereof.

FIG. 1

FIG. 3

FIG. 5

FIG_2

FIG_4

FIG_6
